UNITED STATES PATENT OFFICE.

GEORGE A. WEBER, OF NEW YORK, N. Y., ASSIGNOR TO THE WEBER RAILWAY JOINT MANUFACTURING COMPANY, OF NEW YORK, N. Y., A CORPORATION OF WEST VIRGINIA.

INSULATED JOINT.

SPECIFICATION forming part of Letters Patent No. 744,834, dated November 24, 1903.

Application filed April 15, 1903. Serial No. 152,743. (No model.)

To all whom it may concern:

Be it known that I, GEORGE A. WEBER, a citizen of the United States, and a resident of the borough of Manhattan, city, county, and State of New York, have invented certain new and useful Improvements in Insulated Joints, of which the following is a specification, accompanied by drawings.

My invention relates to railroad-rail joints, but more particularly to that class known as "insulated" joints.

The objects of my invention are to improve upon the construction of such joints and increase their efficiency with simplicity of construction and additional strength of parts.

To these ends my invention consists of apparatus for carrying out the above objects embodying the features of construction, combinations of elements, and arrangement of parts, substantially as hereinafter fully described and claimed in this specification and shown in the accompanying drawings, in which—

Figure 1 is a side view of a rail-joint embodying my invention. Fig. 2 is a plan view of Fig. 1. Fig. 3 is a transverse sectional view taken on the line X X of Fig. 1.

In the construction of insulated rail-joints it is not always necessary to provide insulating material beneath the bases of both rails, but only beneath one of them, and therefore suitable compensation must be afforded for the other rail, beneath which no insulation is placed, in order to maintain the rails in surface. Suitable blocks or cleats or thickened portions of metal in the form of plates may be provided upon the base of the angle-chair to maintain the rails in surface and alignment; but according to my invention a compact, strong, and efficient joint is obtained, while the use of blocks or cleats or thickened portions of metal upon the rail-chair is avoided.

Referring to the drawings, an insulated joint is shown in which the rails A and B, supported upon the rail-chair C, are of the same weight and height. There is a sheet of insulating material D arranged beneath the base of one of the rails, as B, and in order to compensate for the thickness of the insulat-

ing material D in this instance the angle-chair is corrugated, as shown, over a portion of the base E. The corrugations F are of sufficient height above the level of the plane surface of the base E to bring the rails into surface, and at the same time a firm support is provided for the end of the rail, which is not deranged by traffic.

The corrugations F may be formed upon the base of the angle-chair by any suitable means, and they may extend either longitudinally of the chair, as shown, or transversely thereof, as desired. These corrugations may have any suitable or desired size and dimensions to meet the conditions required. I am not to be understood as limiting myself to corrugations of the form shown, for rail-chairs such as shown in my copending applications, Serial Nos. 152,739 and 152,742, filed April 15, 1903, may be used with the insulated joints described and with other insulated joints.

I have chosen to illustrate one form of insulated joint for carrying out my invention, and I am not to be understood as limiting myself to this particular form of joint. In the form of insulated joint shown it will be seen that suitable insulating filling-blocks K, in this instance of wood, are arranged adjacent the webs of the rails, one of said blocks being arranged between the webs of the rails and the upright of the angle-chair and the other block being arranged between the longitudinally-extending strengthening bar or band L, which may be of metal, and the webs of the rails. Suitable bolts O secure the parts of the joint together, and means are provided for insulating the bolts from the upright of the angle-chair and from the strengthening-bar L, suitable insulating-washers P and sleeves Q being provided for that purpose. Means are provided for maintaining the insulation D firmly in position beneath the base of the rail B, in this instance said insulation being extended upwardly between one of the blocks K and the upright of the angle-chair, so that when the nuts R are tightened the upwardly-extending portion of the insulation is tightly clamped between the block K and the angle-chair.

I do not herein claim, broadly, an insulated

rail-joint embodying the strengthening strap or band extending across the joint opposite the upright of the chair, as insulated joints embodying this feature in various forms are 5 claimed in my copending applications, Serial Nos. 63,124 and 63,125, filed June 4, 1901; Serial No. 87,053, filed December 24, 1901; Serial No. 124,193, filed September 20, 1902, and Serial No. 133,770, filed December 3, 1902, 10 nor do I herein broadly claim the insulated step-joint disclosed in my copending application, Serial No. 147,613, filed March 13, 1903.

Obviously some features of my invention 15 may be used without others, and my invention may be embodied in widely-varying forms.

Therefore, without limiting myself to the construction shown and described nor enumerating equivalents, I claim, and desire to 20 secure by Letters Patent, the following:

1. An insulated rail-joint comprising the meeting ends of rails, an angle-chair having a base and an upright, one portion of the base of the angle-chair being provided with corrugations integral with the chair, one of said rails being supported upon the corrugations, and the other of said rails being supported upon a sheet of insulation upon the uncorrugated portion of the base of the chair, filling- 25 30 blocks arranged along the webs of the rails, one of said blocks being arranged between the webs of the rails and the upright of the angle-chair, a metallic strengthening bar or band extending across the joint outside of the other blocks, and bolts for securing the parts of the 35 joint together, said bolts being suitably insulated by insulating washers and sleeves, for substantially the purposes set forth.

2. An insulated rail-joint, comprising the 40 meeting ends of rails and means for supporting said rails in surface consisting of a base-plate having a corrugated portion for one of

the rails, means for insulating one of the rails from said base-plate, bolt-plates and means for insulating said bolt-plates from the rails, 45 and insulated bolts for securing the parts of the joint together, for substantially the purposes set forth.

3. An insulated rail-joint, comprising the meeting ends of rails and means for supporting said rails in surface consisting of a base-plate, one portion of its surface being pressed outwardly beyond the remainder for one of the rails, means for insulating one of the rails from the base-plate, and insulated means for 50 maintaining the rails in alinement, for substantially the purposes set forth.

4. An insulated rail-joint, comprising the meeting ends of rails and means for supporting said rails in surface consisting of a rail-chair having a base and an upright, a portion 60 of the surface of the base being pressed outwardly beyond the remainder of the surface for one of the rails, insulated means for maintaining the rails in alinement, and insulated 65 bolts for securing the parts of the joint together, for substantially the purposes set forth.

5. An insulated rail-joint, comprising the meeting ends of rails and means for supporting said rails in surface, consisting of a base-plate, one portion of its surface being pressed outwardly beyond the remainder for one of the rails, means for maintaining the rails in alinement, and means for insulating the rails 70 from each other, for substantially the purposes set forth.

In testimony whereof I have signed this specification in the presence of two subscribing witnesses.

GEORGE A. WEBER.
